UNITED STATES PATENT OFFICE.

DANIEL E. MIESS AND ALVYN RODNA MIESS, OF LOS ANGELES, CALIFORNIA.

HEEL PROTECTOR.

Application filed December 19, 1921. Serial No. 523,336.

To all whom it may concern:

Be it known that we, DANIEL E. MIESS and ALVYN RODNA MIESS, both citizens of the United States, and residents of Glendale, 5 county of Los Angeles, State of California, have jointly invented new and useful Improvements in Heel Protectors, of which the following is a specification.

This invention relates to devices for protecting the heels of shoes from wear, abrasion, and scuffing; and although the device of this invention is intended primarily for use by women when driving an automobile, it will be understood that the invention is 10 not at all limited to such use, nor its advantages limited to such a situation. However, the invention will be best understood by describing it as used by an automobile driver.

It is universally complained of that the 20 heel portion of a woman's shoe, when the foot is placed upon the foot throttle, comes into contact with the automobile floor boards, and the heel is thereby abraded and soiled. Our invention provides a simple and 25 effective means for protecting the heel; provides a device that may be very easily and quickly applied or removed, and a device that may be very easily adjusted to fit properly. These features of the invention, together with others, will all be apparent from 30 the following detailed description of a specific and preferred form of the device, reference for this purpose being had to the accompanying drawings in which—

Fig. 1 is an elevation showing the device in use; Fig. 2 is a plan view of the device, approximately full size; Fig. 3 is a reverse plan of the same; Fig. 4 is a view similar to Fig. 2, but showing the securing cords in 40 another position of adjustment; Fig. 5 is a side elevation of the device; Fig. 6 is a section taken as indicated by line 6—6 on Fig. 2; and Fig. 7 is a view similar to Fig. 1 showing a modified form.

The body of the protector comprises a more or less semi-spherical part 10 of a proper shape to fit around the heel portion of a woman's shoe, and adapted to cover that heel portion so that when the heel is resting 50 upon the floor, it will be this body 10 which comes into direct contact with the floor. The body 10 may preferably be made of leather and may preferably be made in two layers as indicated at 10^a and 10^b in Fig. 6; the 55 inner layer being made of a soft leather for direct contact with the shoe, and the outer

layer being made of any suitable leather with any desired color and finish. The whole body is preferably more or less flexible, so as to properly fit the heel; and this flexibility furthermore gives a better non-slipping contact with the automobile floor board. 60

At opposite sides of the body 10 there are loops 11 and 12, made of soft pliable leather and secured to the body by having the edges of the leather that forms the loops sewed in between the two layers 10^a and 10^b. These two layers 10^a and 10^b may be stitched together around their edges by stitchings as indicated at 13; and this same stitching may 70 serve to hold the loops 11 and 12. One end of an elastic cord 20 is permanently secured at 21 in one of the loops, say the loop 12, by suitable stitching. This cord, extending 75 from its fastened end at 21, extends out and then back through the loop 12, to form a cord loop 20^a. The cord 20 then extends from this loop 20^a through the loop 12 and around on the other side of body 10, as indicated in the part 20^b, and then extends 80 through the loop 11, extends on, as indicated at 20^c, and has at its end a button 22 adapted to be passed through the loop 20^a in the manner illustrated.

When the device is to be used, the cord part 20^c is passed under the shoe forward of the shoe heel 30, the body 10 is placed over the heel part of the shoe, and then the loop 20^a and the part 20^b are brought forward over the ankle and the button 22 is passed 90 through the loop 20^a. Adjustment having been properly made so that there is a suitable tension on the elastic cord, this one fastening of the button 22 in the loop 20^a serves completely to hold the whole device in place. 95 In order to adjust the device to different wearers, it is only necessary to adjust the effective length of elastic cord 20; which may be done by adjusting the lengths of loops 20^a. It will be apparent that if loop 10^a 20^a is lengthened, the effective length of the elastic cord is shortened; whereas if the loop 20^a is shortened, the effective length of the elastic cord is lengthened.

In Fig. 7 we show a modified form of body 10^a that is adapted not only to cover the back or heel portion of the shoe but also the shoe heel itself. Otherwise this form is as previously explained.

It will thus be seen that we have provided 110 a very simple, easily applied, and easily adjusted device for protecting the heel portion

of a shoe. Its superiority lies largely in its ease of application (only one fastening having to be made) and its ease of adjustment; and although we have described a particular and specific form of our device, we do not wish to be specifically limited to those particulars, except as expressly so stated in the following claims.

Having described a preferred form of our invention, we claim:

1. A heel protector, embodying a body portion adapted to be applied to and cover the heel portion of a shoe; a securing cord connected at one end to the body, extending therefrom and then back on itself to form an adjustment loop at one side of the body; means at two sides of the body forming loops through which the cord slidably extends and forms, between said body loops at the side of the body opposite to that first mentioned, a portion adapted to encircle the heel of a shoe; and the free end of the cord extending to the first mentioned side of the body and having a member adapted to be engaged in the adjustment loop, thereby forming with said adjustment loop a portion adapted to encircle the ankle; the cord, other than its said attachment to the body and its passage through the body loops, being free of the body.

2. A heel protector, embodying a body portion adapted to be applied to and cover the heel portion of a shoe; a securing cord connected at one end to the body, extending therefrom and then back on itself to form an adjustment loop at one side of the body; means at two sides of the body forming loops through which the cord slidably extends and forms, between said body loops at the side of the body opposite to that first mentioned, a portion adapted to encircle the heel of a shoe; and the free end of the cord extending to the first mentioned side of the

body and having a member adapted to be engaged in the adjustment loop, thereby forming with said adjustment loop a portion adapted to encircle the ankle; said cord being elastic and being, other than its said attachment to the body and its passage through the body loops, free of the body.

3. A heel protector, embodying a body portion adapted to be applied to and cover the heel portion of a shoe; loops at opposite sides of the body; an elastic cord secured to the body near one of its loops and extending out and then back on itself to form an adjustment loop, extending then slidably through the said body loop and then around the side of the body and slidably through and beyond the other body loop; and a button on the free end of the cord; the cord, other than its said attachment to the body and its passage through the body loops, being free of the body.

4. A heel protector, embodying a body portion adapted to be applied to and cover the heel portion of a shoe; a securing cord attached at one end to the body and doubling back on itself to form an adjustment loop, and the other end of the cord having a member to engage the adjustment loop; means at two sides of the body forming loops through which the cord slidably extends and forms at one side of the body a portion adapted to encircle the heel of a shoe, and forming at the other side of the body a portion adapted to encircle the ankle, both encircling portions being adjustable as to size by sliding the cord through the loops.

In witness that we claim the foregoing we have hereunto subscribed our names this 10th day of December, 1921.

DANIEL E. MIESS.
ALVYN RODNA MIESS.

Witness:
VIRGINIA BERINGER.
